OIL IMPREGNATED CONDENSER

Charles H. Caine, Chicago, Ill., assignor to
 Brown & Caine (Chicago Division), of Tung-
 Sol Lamp Works, Inc., Chicago, Ill., a corpo-
 ration of Delaware

Application September 23, 1929
 Serial No. 394,415

8 Claims. (Cl. 175—41)

This invention relates in general to electrostatic condensers, more specifically to oil impregnated condensers; and to means for clamping and sealing such condensers in a suitable container.

Condensers of the paper-foil type are extensively used as by-pass condensers in radio sets and in power packs therefor, for power factor correction, and for other similar uses. These condensers are usually formed by rolling a pair of metallic foils with suitable insulation, usually paper, interposed between adjacent layers of the foil, and the assembly so formed is impregnated with a suitable, dielectric compound and pressed into the desired shape.

Thin metallic terminals are usually interposed between the layers of insulation and in contact with the foils or plates of the condenser and brought out to suitable terminal lugs to which the wires leading to the external circuit of the condensers are attached.

In encasings or housings of this type it has been the frequent practice heretofore to place the compressed assembly in a suitable metallic can, and to wedge the unit in the can by cardboard or other suitable strips placed around it. The assembly so constructed is finished by pouring molten insulation, frequently an amorphous substance such as wax or an asphaltum derivative, into the can over and around the condenser unit.

Condenser blocks such as are commonly used in power packs for radio sets and the like, comprise a plurality of condensers encased in a suitable container, with the terminals of the individual condensers attached to a suitable terminal block upon which the external leads are led. These multi-unit blocks are frequently finished in the above described manner.

Condensers of this type are subject to the criticism that the impregnation of the condenser unit is not complete and wholly moisture-proof with the result that cracks frequently form in the wax impregnation of the unit and moisture penetrates the condenser through these cracks causing an eventual break-down of these units.

Moreover, the cardboard wedges employed to press the condensers unit in the can or housing prevent a free flow of the molten insulation around the unit in that housing with the result that the condensers unit is not perfectly sealed in the can.

In my present invention I manufacture a condenser unit by rolling the foils and insulation in the above manner and impregnate it in a suitable oil, preferably a mineral oil which is high-

ly refined to lower its carbon content. Preferably the impregnation is preceded by a vacuum treatment which withdraws the moisture from the structure, and the impregnation made with the oil and under considerable pressure so as to ensure removal of all traces of moisture and perfect penetration of the oil into the insulation of the condenser.

In the preferred form of my invention I mount the unit so constructed in a clamping device which holds the plurality of units forming the condenser block rigidly together and also spaces the block so formed away from the walls of the can or casing in which it is enclosed. As a result when the molten insulation material is poured into the can it flows freely around the condenser block and completely moisture-proofs and seals it. Since the unit is spaced away from the walls of the container there is room for an appreciable thickness of compound around it and the seal is thereby made perfectly and is lasting.

The oil with which the condenser units have been impregnated comes in direct contact with this outer sealing compound, which must therefore be amorphous and so constituted that it will not be deteriorated or decomposed by the oil if a perfect seal is to be maintained. I have found that a compound comprising a combination meets these requirements. This compound does not emulsify with the oil, and is not crystallized or decomposed in any way by contact with it. Doubtless many other compounds may also prove suitable for this purpose, and I am not therefore to be limited to the use of any particular compound.

In one embodiment of my invention the condenser is mounted with the cover of the can on the bottom side and the lead-out wires projected out through that cover. In other adaptations the housing is mounted upright and the conductors brought out through the top of it. These and many other arrangements for mounting the housed condenser, are contemplated and are within the teachings of my invention.

Now, to acquaint those skilled in the art with the teachings of my invention reference is made to the drawing in which a preferred embodiment of it is illustrated by way of example, and in which:

Figure 1 is an elevational view of a completely assembled condenser;

Figure 2 is a plan view of the condenser with the cover removed and showing the terminal block;

Figure 3 is a cross sectional view taken along

the line 3—3 of Figure 2 looking in the direction of the arrows;

Figure 4 is a cross sectional view taken along the line 4—4 of Figure 3 looking in the direction of the arrows;

Figure 5 is a detailed view of one of the clamping members;

Figure 6 is a detailed view of the other clamping members.

10 The condenser illustrated is an electro-static condenser suitable for use as a by-pass condenser in a power pack such as would be used to furnish current for a radio set or the like, and comprises the condenser units 1, 2, 3, 4 and 5 which are encased in a single casing from which electrical connections 6, 7, 8 and 9 are led through the cable 10. As shown, terminals 11, 12, 13, 14 and 15 of the separate condenser units are commoned and connected to the conductor 9 leading from the condenser block.

15 The opposite terminals are indicated at 16, 17, 18, 19 and 20, with terminals 16 and 17 commoned and connected to the lead 6, terminal 18 connected to the lead 7, and terminals 19 and 20 commoned and connected to the lead 8. The 25 particular manner of connecting up the various condensers forming the block is not of the essence of the present invention as any desired arrangement of the condensers in the block is possible within the teachings of my invention.

30 The condensers as shown are each constructed of a plurality of convolutions of two metallic foils with paper insulation interposed between them, the dimensions of the foils and thickness of the paper being governed by the desired capacitance and insulation characteristic of the condenser unit.

35 The condensers so formed are grouped together as shown and held by a clamp which comprises two side pieces 21, and two end pieces 22. The side pieces 21 are provided with inwardly depending grooves 23 and 24, best seen in Figures 4 and 5, which are brought into registration with hook-like flanges 25 and 26 formed in the edges 45 of the end plates 22. The interaction of the plates so hooked together firmly binds the condensers 1 to 5, inclusive, together and holds them securely as a unit.

40 The side plates 21 are also provided with upwardly depending feet 27 and 28 upon which the terminal block 29 rests. Another projection 30 extends upward from this end of the plate 21 and lies in the slot 31 in the block 29, the extreme 45 end portion 32 of this projection being bent over adjacent to the upper side of the terminal block to securely lock it in place on the assembly.

45 This terminal block 29, is thus rigidly supported in the manner of a bridge over the end of the condensers, and serves as rigid terminal for the 50 contacting strips 11, 12, 13, 14, 15, 16, 17, 18, 19, 20 of the condensers. These strips are preferably made of very thin metal and since they are held in contact with the plates of their respective condensers only by friction, it is imperative that they 55 be rigidly supported so that strains placed on them by the wires of the connecting cable, will not dislodge them from the assembly.

60 In the manufacturing of condensers of this type, the clamping of the units and terminal block in the above manner proves advantageous for the reason that the rigidity of the assembly permits soldering the terminals together before the units are impregnated. This insures a good joint 65 since the contacting strips 11—20 inclusive are 70 clean at this time and can be easily fluxed and

readily soldered. The rigid bridge-like terminal block 29 supports the thin terminals to facilitate soldering them, and also prevents the flow of soldering flux along the terminal into the condenser assembly.

65 After the terminals have been soldered together the condensers, clamping members and terminal strip are all immersed in an impregnating bath. Preferably the impregnation of the condensers is accomplished by the usual vacuum process, the details of which are not of the essence of the present invention and are so familiar to those skilled in the art that a description of them is not necessary herein.

70 The material used to impregnate these condensers may be varied within the teachings of my invention. For certain purposes I have found that highly refined petrolatum, which is semi-solid at ordinary room temperatures, is a very satisfactory impregnating medium. In other instances I have found that vegetable oils of similar viscosity at ordinary temperatures are preferable. In certain types of condensers I use a mixture of vegetable and mineral oils to secure the desired characteristics. The choice of the particular impregnating medium will, of course, depend upon the desired characteristics of the finished condensers. Ordinary paraffin wax may also be used when desired, within the teachings of my invention.

75 In practice I have found it advantageous to place a large globule or lump of solder on the terminals when they are soldered together, that supply being subsequently used to attach the terminal wires from the cable 10 to the terminal, that operation taking place in the final assembly, and after the units have been impregnated. Even though the terminals are then covered with the impregnating compound, a good electrical joint can be made between the wire and terminal since the solder which makes this joint is already in clean contact with the terminal. The wires are tinned previously and the joint can be quickly and cheaply made by laying the wire on the globule of solder and heating it until the solder melts.

80 The lower edge of the plate 21 is provided with the clamping member 33 which is bent inward before the condenser has been assembled to prevent the condensers from slipping downward through the clamp, as will best be seen in Figure 3.

85 As shown the condenser 5 is smaller than the other units in the block, and it is therefore necessary to insert a spacer 15' between the condensers 2 and 3 together with the condenser 5 to fill up the void that would otherwise be left between these condensers.

90 This filler 15' may be cardboard or any other preferred material.

95 In condenser blocks such as are used in power packs, the high voltage encountered makes it desirable to insulate the individual condenser in such a manner that there is no likelihood of a flashover to ground.

100 To this end I have provided the insulating member 21' which surrounds the five condensers shown and prevent them from coming into electrical contact with the metallic clamping plates 21 and 22. This insulation 21' may be fiber, heavy paper, or any other preferred sheet material. Also the condenser 5 is insulated from the condensers 2 and 3 by a sheet of insulation 2' to increase the insulation resistance between those units, and to prevent creasing of those units by the pressure exerted on them by the unit 5.

105 To protect the condenser blocks so formed from

mechanical injury and from the ingress of moisture I have provided the can 39 which is rectangular in shape and constructed of suitable sheet metal such as tin or brass, this can 39 being of such 5 dimensions that the condensers held together by clamps 21 and 22 freely slide into it. As will be best seen in Figure 3, the condenser so disposed in the can is supported up or above the bottom thereof by the feet 34 and 35, and spaced away 10 from the side of the can by the ears 38 which are formed as projections in the surface of the end plate 22.

Similar projections 36 and 37 formed in the 15 surface of the side plate 21 space the condenser block away from the side walls of the can in a similar manner.

Preferably the can is of such a height that it extends well above the upper surface of the terminal block 29, and in one preferred embodiment 20 of my invention it is provided with a metallic cover 42 containing the bushing 41 and the screws 44 and 45, the latter being projected through openings in the cover and securely soldered in these openings as shown at 47.

25 These screws 44 and 45 facilitate mounting the block on a suitable support with the cover on the bottom side of it.

The condenser unit is assembled by placing the condenser block in the can, attaching the 30 electrical conductors of cable 10 to the proper binding posts, and then filling the can with an insulation material which may be, a waxy compound, an asphaltum derivative, or any other preferred amorphous material. Since the condenser block is supported up off of the bottom of the can, this insulation flows beneath the block and perfectly seals that end of the block. Also 35 since the clamping plates 21 and 22 are spaced away from the walls of the can, the insulation flows freely around it forming a body of appreciable thickness which seals the side surfaces of the block.

In the preferred embodiment of my invention, sufficient molten insulation preferably asphaltum or a mixture of asphaltum and wax is 40 poured into the can to completely fill the space above the terminal block and surrounding the end of the cable 10, and the cover 42 is placed into place while this insulation is still hot causing it to adhere to the inside surface of the cover which is then soldered into place in the usual manner. This completely seals the condenser block in the can and guards against the 45 possibility of moisture entering the condensers by creeping along the cable. The cable 10 is itself moisture-proofed by impregnation in suitable compounds.

The particular sealing compound employed 50 will depend upon the impregnating material used in the condenser units, as the two materials are to be chemically and mechanically neutral so that there will be no mixing of the two during the manufacture and operation of the unit.

While the preferred embodiment of my invention 55 contemplates mounting the condenser with the top down and therefore sealing it with a solid or semisolid sealing material, the seal may also be transil oil, or other similar insulating oil, and the can suitably mounted upright.

70 While I have chosen to illustrate my invention by disclosing a preferred embodiment of it, I have done so by way of example only as there are many modifications and adaptations which can be made by one skilled in the art without 75 departing from the teachings of the invention.

Having thus complied with the statutes and shown and described the preferred embodiment of my invention, what I consider new and desire to have protected by Letters Patent is pointed out in the appended claims.

80

What is claimed is:

1. In combination, a container, a plurality of condenser units, a clamp forming a closed loop about said units, said clamp comprising pairs of side parts having hooked engagement for closing the loop about the condenser units, said side parts having integral extensions projecting below the condenser units for spacing said units from the bottom of the container, and integral tabs struck out from opposite sides of the side parts for spacing the condenser units from the sides of the container.

2. An electrical condenser unit comprising a plurality of separate condensers, a terminal block on which the terminals of said separate condensers are grouped and connected to a cable leading outward from the unit, a metallic clamp for holding said condensers together and also attaching the terminal block thereto, spacing means on said clamp, a can for housing said unit, the walls of the can being spaced away from said unit by said spacing means, and a moisture-proofing compound surrounding said condensers and terminal block.

3. An electrical condenser unit comprising a plurality of separate condensers, a clamp for holding said condensers together, terminals on said condensers, a terminal block formed of an insulating material and supported on said clamp adjacent to said condensers, said block having 105 slots in which said terminals are supported, a can in which said condenser is housed, and means on said clamp for supporting the condensers in said can and for spacing them away from the walls thereof.

115

4. A clamp for holding condensers together comprising four rectangular sheet metal members two of which have grooves formed on their sides and a pair of feet and a clamping member formed in their ends, the other two members 120 having semi-circular flanges formed in their sides and a pair of feet formed in one of their edges, certain of said feet supporting the condensers and clamped in a suitable housing and others of said feet supporting a terminal block 125 on the condensers, said clamping members holding said condensers and terminal block in place, and a plurality of ears formed in said four members for spacing said condenser in the housing.

5. A bracket for compressing the units of a 130 condenser block and for holding them within a protective casing comprising four metallic plates fitted on the sides and ends of the block, said end plates being channeled and said side plates being fitted within said channels to compress the 135 block, feet projecting from one edge of said end plates to support the block, retaining lips projecting from one edge of said side plates to support the block in the bracket, and a plurality of spacers projecting from the surfaces of said 140 plates to space the block and bracket.

6. In a condenser block, the combination with a plurality of paper-foil condenser units having terminals connected together and connected to leads extending outward through the can in 145 which the condensers are housed, of a sheet of insulation wrapped around said condensers a metallic clamp surrounding the condensers and insulation, said clamp comprising four plates joined together at their adjacent edges by flanges, and 150

a plurality of ears projecting outward from the faces of said plates to space the condensers in said can.

7. In combination, a plurality of condenser units, a clamp forming a closed loop about the condenser units for clamping said units together, said clamp comprising side portions having extensions projecting above the tops of the condenser units, and a terminal supporting member connected with said clamp by engagement with said extensions.

8. In combination, a plurality of condenser units, a clamp forming a closed loop about the

condenser units for clamping said units together, and a container, said clamp having opposite side portions provided with opposite projections engageable with the sides of the container to space the condenser units away from the side walls of the container, the internal width of the container being substantially equal to the distance from the tip of one of said projections to the tip of the opposite projection whereby the opposite projections fit against the opposite side walls and position the condenser substantially centrally therebetween.
